UNITED STATES PATENT OFFICE.

LUIGI GUSSALLI, OF BRESCIA, ITALY.

SCREEN FOR SUN CURES.

Application filed June 22, 1926, Serial No. 117,812, and in Italy July 11, 1925.

It is difficult to employ sun-cures at the homes of sick persons, because it is almost always impossible to arrange a handy and cheap shelter which will afford free passage 5 to the sun radiations while screening the patient from without.

The present invention relates to such a screen, which may conveniently be attached to curtains, folding screens or the like, and 10 which allows the sun rays to pass freely through it while at the same time preventing the patient from being seen by people standing outside the shelter and screen.

Such a screen is characterized by a flat 15 board of any desirable shape, made out of light stuff, as paper, wood, cork or similar material, pierced by a great number of apertures divided from each other by very thin walls and forming a sort of "honeycomb".

20 In one of the forms of construction, considered as most appropriate, the screen is made out of undulated card-board strips whose width is equal to the thickness of the screen, wound up in a shallow spiral.

25 The accompanying drawing shows in Fig. 1 by way of example a perspective view of part of a screen according to the present invention and in Fig. 2 a perspective view of part of a screen built up in the manner suggested above; Fig. 3 is a side elevation, with 30 parts in section, representing the screen as mounted on a tripod.

In all screens built according to the present invention, a board having any convenient 35 shape or dimensions, is pierced by a great number of apertures 1, round, square, rectangular, hexagonal, triangular or of any other shape. Such apertures 1, which may be either perpendicular or inclined to the 40 faces of the board, but are always parallel to each other, are divided by very thin walls 2—2', 3—3', so as to form a general surface of least opacity in the direction in which it has to be crossed by the sun's rays, that is, 45 parallel to the divisions of the apertures. On the other hand, said apertures are small enough and have such a depth 4 as to screen all lateral visibility in directions not parallel to the aperture divisions or to the sun's rays. 50 Screens of this type can be built in many ways, and in accordance with any of the well-

known methods; however, the method illustrated in Fig. 2 is now considered the most satisfactory, as it secures perfectly parallel apertures in a rigid and light screen which 55 can be manufactured in a simple and cheap way with strips of undulated cardboard of the kind usually employed for packing. This kind of undulated cardboard is obtained by gluing to a sheet 5 of light, flexible card- 60 board an undulated sheet 6 of the same material; and in utilizing it, long strips thereof are cut perpendicularly to the waving 6 and rolled in a shallow spiral on a central core 7 (Fig. 3) of any convenient shape, after applying glue to the back of strips 5 or to the crests of the waving 6. A satisfactory screen 65 can be constructed by using strips of waved cardboard 2 inches wide, having undulations $\frac{1}{4}$ inch high and with $\frac{1}{2}$ inch pitch, and building up a disc therefrom having a diameter of about 1 yard.

The disc 8 thus produced is flat and circular if the central core 7 is a cylinder; but it 70 can be given any other desired shape by varying the shape of the core, and it is also possible to obtain discs whose faces are not flat, as, for instance, by using strips of variable width. The disc can be reinforced at 75 its rim by a band or border 9 (Fig. 3) of fabric, wood, metal or other suitable material; and it can be mounted on a support 10 similar to a camera tripod, having a universal joint 11 between it and the central spindle 12 whereon the core 7 is secured. Such spindle may be provided with an extension or handle 13, which allows the screen 80 to be turned easily toward the sun.

Having now described my invention what I claim as new and desire to secure by Letters Patent is:

1. A screen for sun-cures, comprising a disc formed of alternating undulated and plain strips of equal width wound spirally upon themselves, with the crests of the undulations attached to the adjacent faces of the plain strips; the spaces defined by the undulations being open from end to end to permit unobstructed passage of the sun rays there-through and having a length which is greater 100 than the height of the undulations so as to cut off vision through said spaces excepting

in directions parallel with the axes thereof.

2. A screen for sun-cures, comprising a disc of honeycomb formation and of substantial thickness having a multitude of apertures which open unobstructedly through its opposite faces to permit free passage of the sun rays therethrough; said apertures hav-

ing a length which is appreciably greater than their width so as to cut off vision through them except in directions parallel with their axes.

In testimony whereof I affix my signature.

LUIGI GUSSALLI.
